[57] CLAIM

The ornamental design for a combined magazine, memo pad, and pencil rack, as shown and described.

DESCRIPTION

FIG. 1 is a perspective view of a combined magazine, memo pad and pencil rack showing our new design; FIG. 2 is a front elevational view thereof; FIG. 3 is a top plan view thereof; FIG. 4 is a bottom plan view thereof; FIG. 5 is a left side elevational view thereof; FIG. 6 is a right side elevational view thereof; FIG. 7 is a cross-sectional view taken along line 7—7 of FIG. 2; FIG. 8 is a cross-sectional view taken along line 8—8 of FIG. 2; FIG. 9 is a perspective view of a modified form of the combined magazine, memo pad and pencil rack; FIG. 10 is a front elevational view thereof; FIG. 11 is a top plan view thereof; FIG. 12 is a bottom plan view thereof; FIG. 13 is a left side elevational view thereof; FIG. 14 is a right side elevational view thereof; FIG. 15 is a cross-sectional view taken along line 15—15 of FIG. 10; FIG. 16 is a cross-sectional view taken along line 16—16 of FIG. 10; FIG. 17 is a perspective view similar to FIG. 9, the broken line showing of a magazine, memo pad and pencil being for illustrative purposes only; FIG. 18 is a cross-sectional view taken along line 18—18 of FIG. 10; and FIG. 19 is a cross-sectional view taken along line 19—19 of FIG. 10.
